UNITED STATES PATENT OFFICE

GERALD G. GREULICH, OF CLEVELAND HEIGHTS, OHIO, ASSIGNOR TO THE LOCK-STEEL COMPANY, OF PITTSBURGH, PENNSYLVANIA, A CORPORATION OF DELAWARE

MONOLITHIC REINFORCEMENT

Application filed November 19, 1930. Serial No. 496,602.

This invention relates to wall, floor or ceiling constructions and more particularly to burglar-proof reenforced wall, floor or ceiling constructions, such as are used in bank vaults, and the like.

An ordinary concrete wall can be chipped through and broken away quite rapidly, and therefore, in the construction of bank vaults it has been customary to imbed metal reenforcing members in the concrete slabs comprising the walls, floors and ceilings, the reenforcing members being arranged so as to make it difficult to break an opening through the wall large enough to admit a man. The reenforcing material should be constructed entirely of hardened tool-resisting steel, so that a torch would be necessary to cut away the metal. However, most prior reenforcing devices have been fabricated by complicated processes such as bending, crimping and slitting and expanding, and therefore only parts of such prior devices could be made of hardened steel. Also, certain prior constructions and reenforcing devices have been unsatisfactory in that it has been possible to remove a small section of the concrete and metal, and then to strip away large sections of the metal. Others have been objectionable in that they have lacked sufficient structural strength and have been easy to demolish by an explosive force.

An important object of my invention, therefore, is to provide a method of reenforcing a slab of concrete or similar material, so as to render it practically impossible to cut an opening therethrough sufficient in size to admit a man without cutting the reenforcement into small sections. In this connection, my invention also contemplates a reenforcing construction, which enables the parts to be fabricated at the factory, of hardened, tool-resisting steel, compactly nested for shipment, and conveniently handled at the time and place of installation.

An additional object of my invention is to provide a slab reenforcement, which not only has the characteristic of increasing the difficulty of cutting an opening therethrough, but also has the characteristic of increasing the resistance to demolition by explosive force

and to load stresses incident to the collapse of a building by fire or otherwise.

Briefly, my invention contemplates a wall reinforcement made up of a series of units, the units, as adapted for vertical walls, comprising straight vertical end members having bent horizontal cross-members secured thereto. The units are adapted to inter-fit in pairs, and when the pairs are placed in the wall construction, a locking bar, which is adapted to be inserted through openings formed between the cross-members of adjacent pairs of units, is employed to secure the pairs together, thus forming a continuous chain of reinforcements, no section of which can be removed without cutting away each of the bent members, and part of the straight members. The wall may be further reinforced by longitudinally extending horizontal rods, which may be supported by the transverse horizontal members of the units.

A preferred form of my invention is shown in the drawing, in which Fig. 1 is a horizontal section of a concrete slab, embodying my reenforcing members; Fig. 2 is a vertical section, taken along the lines 2-2 of Fig. 1; Fig. 3 is a perspective of two of the units interfitted to form a pair; Fig. 4 is a perspective showing pairs of units interlocked to form a continuous reenforcing chain; and Fig. 5 is an end elevation of the units nested for shipment.

Referring more particularly to the drawing, 10 indicates a concrete slab embodying my burglar-proof reenforcing construction. 85 The metal reenforcing members preferably comprise a series of identical units, and each unit may comprise a plurality of bent cross-members 15, which extend obliquely through the slab, and which may be vertically spaced apart and secured at their ends to end members 16 and 17, by welding, brazing or any other convenient method. All of the various parts of the units are preferably formed of hardened, tool-resisting steel.

Preferably, the cross members are bent at an acute angle, as at 18, and the straight portions extending from the apex of the angle are of unequal length, as this construction distributes the end members throughout the

slab. Locking bars 19, which are adapted to engage the angular portions 18 of the cross members, may be provided to secure adjacent pairs of units together, and the wall may be further reenforced by means of horizontally extending rods 20, which rest on the cross members 15.

The method of assembling the reenforcing material is clearly indicated in Figs. 3 and 4. The first step is to arrange the units in pairs, so that the units in each pair face opposite directions. That is, in the drawing, the cross members extend to the right of the end members, in the units formed by the members 15, 16 and 17; and to the left of the end members in the units formed by the members 15a, 16a and 17a. The two units are then interfitted in pairs, by moving them together, so that the end members 17 engage the cross members 15a, and the end members 17a rest against the cross members 15.

After these units have been assembled in pairs, the pairs of units are placed in the wall in such manner that the bent portions 18 of one pair overlap the bent portions 18a of each adjacent pair, to a sufficient extent to admit a locking bar 19, which is inserted through the opening between the bent portions 18 and 18a.

To further reinforce the slab, the longitudinally extending members 20 may be slid in from the ends of the reenforcing construction before the concrete is poured, and so positioned that they rest on cross members 15. When the reenforcing material has been assembled, the concrete is poured in the usual manner.

The construction, which I have illustrated and described, provides an interlocked reinforcement which resists stresses in every direction. This is apparent, for the straight members are arranged in substantially parallel rows and one of the rows constitutes an interlocking device, which prevents stripping of any of the forms after a small section of the concrete shall have been removed. The use of cross-members, which extend obliquely to the rows offers resistance to a certain method of attacking a wall of this character by a wedge shaped opening, and thereby prevents stripping of large sections of the metal from the concrete.

From the foregoing description of a preferred form of my invention, it will be seen that I have provided a reenforced slab construction, in which the metal reenforcing members are doubly interlocked, and in which the reenforcing material forms, in effect, a chain, no link or section of which can be removed without being completely destroyed. Furthermore, it will be seen that I have provided a reinforcement which may be easily assembled, and manufactured, and which will add to the structural strength of the wall and prevent buckling in case of fire

or explosion. It will also be seen that my reenforcing material is made up largely of a series of identical units, which can be easily shipped in a compact form, and conveniently handled at the time of installation.

I claim:

1. A reenforcement for slabs of building material, comprising rows of longitudinal members, rigid transverse members secured to the longitudinal members and having portions thereof extending obliquely to the rows of longitudinal members, the adjacent transverse members lying in overlapped relation, and means for interlocking some of said members within the slab.

2. A reenforcement for concrete and the like, comprising four rows of longitudinal bars arranged in substantially parallel relationship, bent transverse bars rigidly connecting the longitudinal bars, each transverse bar having a portion thereof extending to one of the outer rows with adjacent transverse members having portions thereof in overlapping relation, and an intermediate row of bars connecting the adjacent sets of cross bars together.

3. A reenforcement for concrete and the like comprising a plurality of fabricated units each having longitudinal members and rigid transverse cross members secured thereto, said transverse members of adjacent units being arranged in overlapping relation, and means for securing the same together.

4. A reenforcement for concrete and the like comprising a plurality of fabricated units each having longitudinal members and rigid transverse cross members secured thereto, said transverse members of adjacent units being arranged in overlapping relation, and means engaging the transverse members to prevent the units from being separated laterally.

5. A reenforcement for concrete and the like comprising a plurality of fabricated units each having longitudinal and rigid transverse cross members secured thereto, the transverse members of adjacent units extending laterally in opposite directions from the longitudinal members so that they overlap when assembled, and means for locking the cross members in overlapped relation.

6. A reenforcement construction for a slab of building material comprising a series of units each including a plurality of rigid longitudinal members and transverse rigid cross members secured to said longitudinal members, said transverse members being bent intermediate their ends to provide portions projecting to one side of the plane of the longitudinal members, said bent portions on adjacent units extending toward each other and lying in overlapped relation, and means for securing the units against lateral separation.

7. A reenforced construction for a slab of building material comprising a series of

units each including a plurality of rigid longitudinal members and transverse rigid cross members secured to said longitudinal members, said transverse members being bent intermediate their ends to provide legs of unequal length projecting to one side of the plane of the longitudinal members, said bent transverse members on adjacent units extending toward each other and lying in overlapped relation within the slab, and means for securing the units against lateral separation.

In testimony whereof, I hereunto affix my signature.
